UNITED STATES PATENT OFFICE.

HEINRICH SCHWEITZER, OF NEW YORK, N. Y.

CENTERED MOLD FOR DENTAL CASTINGS.

1,112,847.

Specification of Letters Patent.

Patented Oct. 6, 1914.

Application filed January 6, 1914. Serial No. 810,571.

To all whom it may concern:

Be it known that I, HEINRICH SCHWEITZER, a subject of the German Emperor, residing at New York, in the county and State of New York, have invented new and useful Improvements in Centered Molds for Dental Castings, of which the following is a specification.

Molds for dental castings heretofore as a rule were only surrounded by a mold ring or frame and a large part of the upper surface of the mold investment compound was subjected to the fluid pressure which is applied in the casting act.

It must be understood that the investment compound for dental castings after it is annealed—for the purpose of evaporating wax patterns—consists of a very porous mass and that a good deal of fluid pressure medium enters the pores on the top surface of said mass when the mold is exposed to fluid pressure. This is a disadvantage as the pressure should act only in the central part of the mold where in a crucible the metal is liquefied by heat. A mold flask with a top surface reduced at right angles as shown in Figure 1 of the accompanying drawing is objectionable because fluid pressure medium does enter the open spaces which are created between the mold and flask by the metal expansion of the annealing flask. For large castings it is desirable to invest the wax pattern in a mold which is free on top and bottom during the process of annealing and to seal the peripheral part of these open surfaces during the act of pressure application.

The object of my invention is to seal the peripheral part of the top surface of a mold during the act of pressure application by a detachable cover provided with tapering surfaces which enable at the same time the centering of the mold upon a receptacle and the base of a casting machine.

Fig. 1 of the accompanying drawing shows in vertical section a mold invested in a flask with the top surface reduced at right angles. Fig. 2 is a lateral view of a cover for a dental mold provided with tapering surfaces. Fig. 3 is a side elevation of a mold with a tapering top surface. Fig. 4 is the top view. Fig. 5 the inside illustration of a mold cover for a dental mold. Fig. 6 is a vertical section of a mold sealed by a cover which in turn is sealed by a head. Fig. 7 is a vertical section of a mold cover. Fig. 8 is a vertical section of a mold surround-

ed by a frame. Fig. 9 is a vertical section of a receptacle for the mold. Fig. 10 shows in vertical section cover, mold with frame, and receptacle. Fig. 11 shows in lateral view with parts in section a complete pressure flask upon the base of a casting machine.

Molds having a diminished open surface on top by reducing the surface at right angles such as for example is shown in Fig. 1 (A) of the accompanying drawing require the annealing of the mold in the frame, B, which is covering the peripheral part, P', of the mold. Annealing of the whole flask naturally ruins after a short time the contact surfaces, the metallic parts expand by heat and a space, S, between mold and frame is created into which fluid pressure medium (gas, air) enters as soon as it is compressed against the mold. To obviate this I have constructed a detachable cover of metal, Y, and a mold provided with tapering surfaces on top. The tapering surfaces, T, Fig. 7, preferably made of conical shape are intended to rest upon the tapering surfaces, P', of the mold, Fig. 8, thus sealing the peripheral part of the mold. The conical top surfaces of the mold as shown in Fig. 3 represent the shape of an ascending taper. The central part of the cover may taper at a different angle but is concentric to the surface of the peripheral part. In the center of the cover is an aperture leaving uncovered the part of the mold which is occupied by the mold crucible, C, Fig. 8. In order to obtain a perfect adaptation of the mold cover upon the mold it is required to place the cover upon the mold investment compound while the latter is in a plastic state or to pour investment compound against the interior surface of the cover. The surfaces, T, of the cover are oiled and separate after the investment compound of the mold has set leaving as a result a mold with smooth tapering surfaces free on top. The detachable mold cover is readjusted over the top surface of the mold after the latter is annealed and the metal is melted in the crucible. The cover is now exposed to radiating heat but a few seconds during the pressure action and the tapering surfaces seal the mold even in case of metal expansion.

The cover is provided with a tapering surface extension, K, Figs. 2 and 5, on the exterior surface in which it can be sealed against a head, H, Fig. 6. The lateral and

bottom surfaces of the mold may have any suitable shape; the mold is preferably surrounded by a round frame, F, Fig. 8, which is resting in its lower margin, E, on the 5 margin, N, of a receptacle, R, Fig. 9. This receptacle, having a tapering surface extension, D, on the outside, is preferably provided with tapering surfaces, U, upon its 10 open face and a mold prepared upon such funnel shaped face naturally has a tapering surface extension in the bottom which is centered upon the receptacle. The mold prepared to fit the receptacle and cover can be centered upon the base, M, of a casting 15 machine by placing the receptacle in the recess, V, Fig. 11, putting the pattern in the mold investment compound surrounded by the frame, F, and cover, Y, in position, and lowering the sealing head, H, before 20 the plastic investment compound has set. The tapering surface, K, of the cover allows for the centering of the mold and flask; the tapering surfaces, T, seal the peripheral surfaces of the mold. No fluid pressure can 25 act upon the mold surfaces; pressure being concentrated upon the crucible part of the mold will force the liquefied metal from the central part to all directions desired and fill the mold cavity completely and most 30 perfectly. The sealing head is connected with a source of fluid pressure, Z, and may have any suitable contact surface for making a seal with the mold cover. In the preferred construction, shown in Figs. 6 and 35 11, it is provided with tapering surfaces on the inside in order to make a seal with the outside taper of the mold cover. The head, H, is guided by the tube, O, which is moving up and down in the vertical perforation, 40 W, leading through the bracket, L, of the base of the casting apparatus. The perforation, W, runs true concentric with the tapered recess, V, thus giving a concentric relation to the receptacle, R, and head, H, 45 between which mold and mold cover are centered.

Having now fully described my invention I claim:

1. In a device for dental castings and the 50 like the combination of a mold and a mold cover, said mold having ascending tapering surface extensions on the upper end for the purpose of making a seal during the act of fluid pressure application, said cover having 55 a central aperture and tapering surfaces surrounding said aperture for sealing the tapering top surface of the mold during the act of fluid pressure application.

2. In a device for dental castings and the like the combination of a mold, a mold 60 cover and a sealing head connected with a source of fluid pressure, said mold having a tapering surface extension on the upper end, said mold cover having a central aperture and tapering surfaces around said aperture for sealing the tapering top surface of the mold in the peripheral parts, said sealing head provided with means for making a seal against said cover.

3. A flask for the preparation of a mold 70 for dental castings and the like and for sealing a mold during the act of casting consisting of a mold frame, a mold receptacle and a cover; said cover having a tapering surface extension with a central aperture and being provided with tapering surfaces on the inside for the preparation of tapered mold surfaces.

4. In a device for dental castings and the like the combination of a detachable mold 80 having an uncovered tapering surface extension on the upper end, a base, a sealing head and a pressure flask consisting of a mold cover, mold frame and mold receptacle; said mold cover having tapering extensions 85 on the interior surface for the formation of tapering mold surfaces, centering the mold and sealing the mold during pressure application in peripheral parts of the top surface, said cover also provided with a central aperture and a tapering extension on the exterior surface surrounding the aperture for making contact with the sealing head, said sealing head connected with a source of fluid pressure and movably 90 adjusted on the base in concentrical relation with said mold receptacle, mold and mold cover substantially as described and shown.

5. In a device for dental castings and the like the combination of a mold, a detachable 100 mold cover and a sealing head connected with a source of fluid pressure; said mold having tapering surfaces on its upper end, said mold cover having tapering extensions on its interior surface for making contact 105 and seal with the upper mold surface, a central aperture and a tapering extension on its exterior surface surrounding the aperture; said sealing head provided with tapering surfaces for making seal and contact 110 with the exterior tapering surface extension of said cover.

HEINRICH SCHWEITZER.
